POST SIZING AND PEELING MACHINE

William Neal Riddick, De Ridder, La.

Application May 31, 1934, Serial No. 728,420

3 Claims. (Cl. 142—32)

This invention relates to a post sizing and peeling machine, the general object of the invention being to provide means whereby a log can be readily peeled and reduced in diameter to provide a post which may be used as a fence post, highway post or the like.

This invention also consists in certain other features of construction and in the combination and arrangement of the several parts, to be herein after fully described, illustrated in the accompanying drawings and specifically pointed out in the appended claims.

In describing the invention in detail, reference will be had to the accompanying drawings where-in like characters denote like or corresponding parts throughout the several views, and in which:

Figure 1 is an elevation of the invention.

Figure 2 is a top plan view thereof.

Figure 3 is a section on line 3—3 of Figure 2.

Figure 4 is a perspective view of one of the yokes for supporting a roller.

Figure 5 is a section on line 5—5 of Figure 1.

Figure 6 is a section on line 6—6 of Figure 1.

Figure 7 is a view looking into the plunger head.

Figure 8 is a view looking into the cutter head.

Figure 9 is a section on line 9—9 of Figure 7.

Figure 10 is a section on line 10—10 of Figure 8.

In these drawings, the numeral 1 indicates a base and the numeral 2 indicates a cylinder horizontally arranged and rotatably supported by the uprights 3 through means of the ball bearings 4. A bell-shaped cutter head 5 has its small end threaded in the front end of the cylinder, as shown in Figure 10, and said head is provided with the curved inwardly extending knives 6 which are preferably arranged as shown in Figures 8 and 10, the inner ends of the knives merging into the cylindrical, rear or inner end of the head which is flush with the internal walls of the cylinder 2. This cylinder, with the cutting head, is rotated from any suitable source of power by a belt 7 or the like. A pair of vertically arranged feed rolls 8 of double frusto-conical shape, is each supported by a yoke 9 having a stem 10 which has a sliding fit in a socket 11 on an upright 12. Upper and lower springs 13 press the two rolls toward each other, as more particularly shown in Figure 3. A pair of pulling rolls 14 is supported in vertical position in rear of the cylinder 2 by the uprights 15, each of which is provided with upper and lower inwardly extending arms 16, the free ends of which form bearings for the roller shafts. These rollers are of spool shape,

as shown more particularly in Figure 6, and are driven from a suitable source of power by belts passing over the pulleys 17 on the lower ends of the shafts.

A pair of brackets 18 extend upwardly from the base in front of the rolls 8 and that bracket which is closest to the rolls is formed with a forked head 19 for supporting a log A and the other bracket is also provided with a forked head 19' for supporting a part of the log and said bracket has an opening therein through which slides a rod 20 which is fastened to a forked member 21 which supports the rear end of the log. A substantially frusto-conical plunger head 22 is connected to the forked member 21 by a bracket 23 and the head is connected with a plunger 24 slidably supported by the uprights 25 and which has a rack 26 thereon engaged by a pinion 27 supported by one of the uprights 25 and driven by any suitable means attached to the shaft 28 of the pinion. A spring 29 has one end connected with one of the uprights 25 and the other end to the plunger and tends to hold the plunger with its head 22 in retracted position, but when the shaft 28 is turned, the plunger 25 and its head are moved forwardly so as to push the log A through the rolls 8 and then through the cutting head 5, which peels the log and reduces its diameter and makes the log of a uniform diameter throughout, after which the end 30 of the log is gripped by the rolls 14, which pull it through the cylinder.

As shown in Figures 7 and 9, the plunger head 22 has located therein a substantially conical member 30 provided with the longitudinally extending teeth 31 which gradually increase in length inwardly, as shown in Figure 9, and this conical member is supported in the head by the springs 32 which contact the side parts of the head and the member 30 and the inner end 40 of the head is formed with a socket 33 for receiving the spherical part 34 attached to the inner end of the member 30. Thus the member 30 can automatically adjust itself to different diameters of logs so that the plunger will push 45 the log into the feeding rolls 8 and these rolls will automatically adjust themselves to different sizes of logs. The cutting head 5 is removable and by providing a plurality of heads of different sizes, logs of different diameters can be 50 cut to provide the posts. A counter-balance ring 35 is attached to the rear end of the cylinder 2.

When the plunger assembly is moved forwardly, the rear end of the log is engaged by the member 31 in the head 22 and thus the log is 55

pushed forwardly so that its front end will engage the rollers 8. The double conical form of these rollers 8 and the specific form of the front end of the plunger assembly will lift the log 5 off the supporting members 18 and automatically center the log both horizontally and vertically with respect to the bell 5 and thus the log will be fed into the bell at the center thereof.

Instead of using the plunger, I may provide 10 an endless chain for feeding the log into the feeding rolls 8.

Thus it will be seen that I have provided simple means for peeling and reducing logs to a uniform diameter to form posts that are perfectly round. This invention will produce a saving in freight to the consumer by removing surplus wood from the posts and a saving in preservatives which are used in treating the posts to preserve the same. The invention also eliminates guesswork in calculating the cubical content for treatment with a preservative and allows for standardization of sizes and grades. It also allows for better utilization of timber by using more of the tree and better control of inventories. 25

While the drawings show the rolls 8 and 14 as vertically arranged, it is to be understood that they may be horizontally arranged and that the rolls 14 can be driven in any suitable manner. 30 Both sets of these rolls are removable from their supporting means so that different sizes of rolls can be used in accordance with the size of the work piece. The cutting means will cut different sizes of work pieces, but I prefer to provide a plurality of the rolls, as the rolls can be changed much more easily than can the cutting device. The rolls 14 are preferably changed each time the cutting head is changed so that a better grip can be had on the finished work by said rolls 14. 35

40 It is thought from the foregoing description that the advantages and novel features of the invention will be readily apparent.

It is to be understood that changes may be made in the construction and in the combination 45 and arrangement of the several parts, provided that such changes fall within the scope of the appended claims.

What is claimed is:—

1. A device of the class described comprising a base, uprights carried by the base, a cylinder horizontally arranged and rotatably supported by some of the uprights, means for rotating the cylinder, a bell-shaped cutting head detachably connected to the front end of the cylinder and having cutting members therein, a pair of feed rollers supported from the base in front of the cutting head, spring means tending to move the 10 rollers toward each other, a pair of pulling rollers supported from the base for receiving the log from the cylinder, means for forcing a log between the feeding rollers and into the cutting head, such means comprising supporting means 15 for the log, a plunger having a head for engaging the rear end of the log, means for reciprocating the plunger, said plunger having a conical member movably supported in its head, and spring 20 means for holding said conical member in a central position, and teeth carried by the internal walls of said conical member.

2. In a device of the class described, a plunger having a head, a conical member movably supported in the head, spring means for holding said conical member in a central position in the head and teeth carried by the internal walls of said conical member. 25

3. A log sizing machine comprising a horizontal cylinder rotatably supported, means for rotating the cylinder, a bell-shaped cutting head connected to the front end of the cylinder and having cutting members therein, a pair of vertically arranged feed rollers each of double frusto-conical shape located in front of the cutting head, spring means tending to move the rollers towards each other, supporting means for a log arranged in front of the rollers, feeding means for pushing the logs from the supporting means 35 between the rollers, said feeding means including a substantially conical member for engaging the front end of the log, the supporting means having the log engaging parts located below the transverse centers of the rollers. 40
